UNITED STATES PATENT OFFICE.

CALVIN A. AGAR, OF EAST ORANGE, NEW JERSEY.

EASEL.

1,134,802.

Specification of Letters Patent.

Patented Apr. 6, 1915.

Application filed September 29, 1913. Serial No. 792,508.

To all whom it may concern:

Be it known that I, CALVIN A. AGAR, citizen of the United States, residing at East Orange, in the county of Essex and State 5 of New Jersey, have invented certain new and useful Improvements in Easels; and I do hereby declare the following to be a full, clear, and exact description of the invention, such as will enable others skilled in the art 10 to which it appertains to make and use the same.

This invention relates to easels and more particularly to that class of easels used in connection with display cards.

15 It has for an object to provide an easel of simple design which may be easily attached to a show card and which, when used in all forms, provides for the reinforcement of the wing of the easel to prevent buckling 20 or sagging.

Another object of this invention is to provide improved means for maintaining the wing in its desired position and for locking the parts of the wing so as to obtain the greatest rigidity.

25 Further objects will be apparent from the following specification, appended claim and drawings in which:

Figure 1 is a perspective view of this 30 type of easel, Fig. 2 is a plan view of the blank.

In easels of this character, it frequently happens that the easel is to support heavy show cards or the like and must maintain 35 said show cards in fixed position for an indefinite period.

As the easels are generally made of card board or other flexible material, it is necessary that the wing of the easel should be 40 reinforced to a certain extent in such a way that the points of the wing which carry the greatest strain must be protected against buckling or sagging.

Referring to the drawing there is shown 45 an easel having a portion 22 which is intended to be glued or otherwise secured to the show card and from this portion wings 23 may be bent as on the lines of scoring 24. In stamping the blank for this easel locking members are formed in the following 50 manner; the lower portion of the section 22 has an increased width as at 25 from which extends a tongue 27 foldable as along the line of scoring 26. This tongue has portions 28 which form recesses 29 and ex-

tending in opposite directions from near the end of this blank 27 are the heads 30 which have reduced necks as shown. The wings 23 are provided at remote distances from the lines of scoring 24 with openings 31 which have an enlargement to admit the heads 30, and a reduced portion to engage the necks of the heads 30.

When the easel as shown is to be set up, the portions 22 and 25 having been glued or 65 otherwise secured to the show card, the wings 23 are opened along the lines of scoring 24, the blank 27 is bent between the wings 23, the recesses 29 are put into engagement with the curved portions of the 70 wings from which the parts 28 are struck and the heads 30 are passed through the enlarged portions of the opening 31, after which the tongue 27 is moved downwardly to cause said blank to positively lock the 75 wings 23 in spaced relation and to reinforce those portions of the wings 23 which are most liable to buckle or sag.

Modifications may be made within the scope of this invention without departing 80 from the spirit thereof and the drawing is submitted for illustrative purposes only.

Having thus described my invention, I claim:

In an easel of the class described, a central portion, wings on the opposite side edges of said central portion, and bendable 85 to extend rearwardly therefrom, a tongue having its body portion struck from said wings and central portion and bendable 90 along a line transverse to the side edges of the central portion to extend between the rearwardly extending wings, the wings being recessed at their inner edges adjacent the line of bend of said tongue, said wings 95 being also provided with openings spaced from said inner edges; heads on the said tongue adapted to engage in said openings and said tongue having shoulders formed thereon adapted to engage the edges of the 100 recessed portions of said wings when said wings and tongue are bent rearwardly from said central portion.

In testimony whereof I affix my signature in presence of two witnesses.

CALVIN A. AGAR.
